United States Patent Office

Des. 189,145
Patented Nov. 1, 1960

189,145

BASE FOR A BOWL OR THE LIKE

Frederic D. Farrell, Rockaway Park, N.Y., assignor to Fondeville & Co. Inc., New York, N.Y.

Filed Apr. 25, 1960, Ser. No. 60,298

Term of patent 7 years

(Cl. D36—2)

Fig. 3.

Fig. 4.

Fig. 1 is a front elevational view of a base for a bowl or the like, showing my new design, with a bowl shown in broken lines for purposes of illustration;

Fig. 2 is a bottom plan view;

Fig. 3 is a side elevational view; and

Fig. 4 is a top plan view thereof.

I claim:

The ornamental design for a base for a bowl or the like, as shown and described.
